UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed May 20, 1926. Serial No. 110,372.

This invention relates to improvements in anti-friction bearings.

One object of the invention is to provide a simple, practical and efficient anti-friction bearing, especially adapted for railway car side bearings, in which the parts are so arranged that the anti-friction element is automatically returned to normal centered position when free from load.

10 A more particular object of the invention is to provide an antifriction bearing of the character referred to which utilizes a plain cylindrical roller interposed between the body and truck bolsters of the car, together 15 with centering means which fit about the exterior surfaces of said roller and are connected to the body and truck bolsters in such manner as to partake of the relative movement therebetween, said centering means being so formed as to permit limited independent movement of said roller with respect thereto under operative conditions.

Other objects and advantages of the invention will more clearly appear from the 25 description and claims hereinafter following.

In the drawing forming a part of this specification, Fig. 1 is a fragmentary front elevational view of the body and truck bolsters of a railway car, showing my invention 30 in position with respect thereto, the center sill of the car and cover plate being shown in section. Fig. 2 is a top plan view of the side bearing showing the same detached from the body and truck bolsters. And Fig. 35 3 is a part elevational, part sectional view of the invention substantially upon the line 3—3 of Fig. 2, and showing a fragment of the truck bolster in section.

In said drawing 10 denotes a truck bolster, 40 and 11 the body bolster of a railway car, said bolsters being adapted to have relative radial movement in opposite directions due to the pivotal mounting at the center portions of said bolsters at the point indicated 45 at 12.

A bearing member 13 is provided which as shown is secured to the upper surface of the truck bolster 10, said bearing member preferably being in the form of a casting provided with a bottom wall 14 forming a bearing surface for the anti-friction element, and with spaced vertically disposed ribs 15—15, which are arranged in substantially parallel relation, and between which the 50 55 anti-friction element is adapted to be dis-

posed, said ribs providing a guide-way for guiding the travel of the anti-friction element across the bolster 10. The bearing member 13 also includes an integral centrally disposed flange 16 providing a securing lug at the outer side of the bearing which is utilized as a securing lug, there being a rivet 17 extending through the flange 16 and the top plate of the truck bolster 10. At the inner side of the bearing member there are 60 provided extensions 18—18 spaced apart and located adjacent the ends of the bearing member, said extensions having rivets extending therethrough for securing the truck bolster 10, said rivets being indicated at 19 70 in Fig. 3.

Preferably formed intermediate the extensions 18—18 on the bearing member 13, is an elongated upstanding boss 20, said boss being provided with a vertically arranged 75 opening 21, which is somewhat elongated and extends longitudinally with reference to the boss 20.

An anti-friction roller 22 is provided which is truly cylindrical in cross section, 80 and of a length slightly less than the width between the ribs 15—15, said anti-friction roller being arranged to roll upon the upper surface of the bottom wall 14 between the ribs 15—15, and to be guided by said ribs 85 during its movement. The radius of said roller is preferably slightly more than the height of the guide ribs 15—15.

The body bolster 11 is provided with a bearing member 23, which is riveted in position, and which presents a flat bearing face 24 adapted to engage the top of the roller 22 when in operative position.

In order to control the position of the roller 22 and to positively return the same to 95 central position dependent upon the relative movement of the bolsters 10 and 11, there is provided a transmitting or yoke member 25. Said transmitting member is preferably of one piece construction, elongated in form, 100 and is provided with an angular portion 26 adapted to fit into the aperture 21 of the boss 20 so as to provide a pivotal connection of said transmitting member with said bearing member. The transmitting member extends 105 outwardly in a horizontal direction from the pivot, and at its outer end is provided with an upstanding pin 27, adapted to fit into an opening 28 in the body bolster 11. Intermediate the ends of the transmitting member, 110

and adjacent the pivotal connection of the same with the bearing member is a frame or yoke portion of the transmitting member which fits about the anti-friction roller 22. 5 The frame portion comprises side members 29-29 and end members 30-30, said side and end members being arranged in substantially rectangular formation and adapted to fit over the exterior surfaces of the anti-friction roller 22, so that swinging movement of 10 said transmitting member will effect movement of the roller 22 when free from load. The side bars 29-29, as well as the end members 30-30 are convex in form as indicated 15 at 31 so as to provide curved surfaces for engagement with the roller 22 and to permit swinging movement of the transmitting member with reference to the roller 22 while the latter travels in a substantially straight 20 line transversely across the bolster 10.

In operation, when the body and truck bolsters approach, the bearing member 24 comes into contact with the roller 22, and upon relative horizontal movement between 25 the ends of the body and truck bolsters, the roller 22 is moved to either side of central position. This movement of the bolsters effects a corresponding swinging movement of the transmitting member 25 upon the pivotal connections thereof with the bolsters, the swinging movement of the yoke with reference to the roller 22 which is traveling in a substantially straight line being permitted by the curved engaging surfaces 31 of the 30 yoke portion. When the bolster portions separate vertically and so free the roller 22, movement of the bolsters 10 and 11 to their normal vertically superposed position, will carry the transmitting member 25 therewith 35 and simultaneously return the roller 22 to a central position with reference to the bearing member 13, the position of the transmitting member 25, and consequently of the roller 22 being controlled at all times by the 40 relative position of the bolsters 10 and 11.

By the above described arrangement, it should be appreciated that a plain solid anti-friction element may be utilized with considerable increase in strength, and that due to 50 the arrangement of the transmitting member, the roller is relatively free thereof permitting swinging of the transmitting member while the roller travels in substantially a straight path, thus permitting all necessary 55 movements of the roller while controlling the position thereof dependent upon the position of the bolsters, so that the roller at all

times is in the proper position to perform its functions and is centered and held in assembled relation with the bearing by means 60 of the transmitting member.

While I have herein shown and described what I now consider the preferred manner of carrying out my invention, the same is merely illustrative and I contemplate all 65 changes and modifications that come within the scope of the claims appended hereto.

I claim:

1. In an anti-friction bearing the combination with relatively movable body and truck bolsters having bearing surfaces thereon; of a rolling anti-friction element interposed between said bearing surfaces and means for effecting displacement of said roller to center the same, including a swinging frame member controlled by the relative movement of said bolsters, said frame member embracing said element and having curved guide faces co-operating with the bearing surfaces of said element on opposite sides thereof. 70

2. In an anti-friction bearing the combination with relatively movable bolsters having opposed bearing surfaces; of a roller interposed between said bearing surfaces; centering means for said roller including a yoke embracing said roller said yoke having oppositely extending arms integral therewith; and means for swiveling the free end portion of said arms to the bolsters respectively. 85

3. In an anti-friction bearing, the combination with a body bolster and a truck bolster of a vehicle, said bolsters being relatively movable; of an anti-friction roller co-operating with said bolsters; a support on each of said bolsters provided with a bearing surface co-operating with the roller, one of said supports having guide means thereon for the roller; and means for centering the roller including a lever having its opposite ends swiveled to said bolsters respectively said lever having a yoke-like section intermediate its ends embracing said roller, the opposite side arms of said yoke co-operating with the opposite side portions of the periphery of the roller to displace the same when the lever is actuated upon relative movement of said bolsters. 90

In witness that I claim the foregoing I have hereunto subscribed my name this 17th day of May, 1926. 100

JOHN F. O'CONNOR.
